CLAIM

We claim the ornamental design for a road weigher for vehicle, as shown and described.

DESCRIPTION

FIG. 1 is a top perspective view of a road weigher for vehicle, showing our new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.
